CLAIM

The ornamental design for an outer covering for earbud case, as shown and described.

DESCRIPTION

FIG. 1 is a front perspective view of the outer covering for earbud case showing our new design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken lines of even length depict portions of the outer covering for earbud case that form no part of the claimed design. The broken lines of uneven length are boundary lines that form no part of the claimed design.
